CLAIM

The ornamental design for a cleaning foot for a floor cleaner, as shown and described.

DESCRIPTION

FIG. 1 is a front perspective view of a cleaning foot for a floor cleaner showing my new design;

FIG. 2 is a front view thereof;

FIG. 3 is a rear view thereof;

FIG. 4 is a right side view thereof;

FIG. 5 is a left side view thereof; and,

FIG. 6 is a top view thereof.

(Continued)

The details of the cleaning foot for a floor cleaner shown in broken lines form no part of the claimed design.
